(57) **CLAIM**

The ornamental design for a bowling ball carrier, as shown and described.

DESCRIPTION

FIG. 1 is a top front right perspective view of a bowling ball carrier, showing our new design;

FIG. 2 is a front elevation view thereof;

FIG. 3 is a rear elevation view thereof;

FIG. 4 is a right side elevation view thereof, with the left side elevation view being a mirror image thereof;

FIG. 5 is a top plan view thereof; and,

FIG. 6 is a bottom plan view thereof.

The evenly-sized broken lines shown in the drawings depict portions of the bowling ball carrier that forms no part of the claimed design.

The unevenly-sized broken lines shown in the drawings form the bounds of the claimed design and form no part of the claimed design.

1 Claim, 3 Drawing Sheets
